UNITED STATES PATENT OFFICE.

JAMES ZALLAS, OF DETROIT, MICHIGAN.

DESIGN FOR A VEHICLE RADIATOR COVER.

Application filed October 19, 1927. Serial No. 23,808. Term of patent 7 years.

To all whom it may concern:

Be it known that I, JAMES ZALLAS, a citizen of the Republic of Greece, who have declared my intention of becoming a citizen of the United States, residing at Detroit, in the county of Wayne and State of Michigan, have invented a new, original, and ornamental Design for a Vehicle Radiator Cover, of which the following is a specification, reference being had to the accompanying drawing, forming a part hereof, and in which,

Fig. 1 is a front elevational view of a vehicle radiator cover showing my new design, and

Fig. 2 is a side elevational view.

I claim:

The ornamental design for a vehicle radiator cover, as shown.

JAMES ZALLAS.
